COFFEE TABLE

Simon V. Waitzman, 195 Hicks St.,
Brooklyn, N.Y. 11201

Filed May 9, 1973, Ser. No. 358,715

Term of patent 14 years

Int. Cl. D6—03

U.S. Cl. D6—175

FIG. 1

FIG. 2

FIG. 3

FIG. 1 is a view in perspective of a coffee table showing my new design;

FIG. 2 is a side elevational view thereof, the other sides being the same; and

FIG. 3 is a top plan view thereof.

I claim:

The ornamental design for a coffee table, substantially as shown.
